UNITED STATES PATENT OFFICE

VINCENT GEHRLEIN, OF ERIE, PENNSYLVANIA, ASSIGNOR TO LOVELL MANUFACTURING COMPANY, OF ERIE, PENNSYLVANIA, A CORPORATION OF PENNSYLVANIA

WRINGER

Application filed September 28, 1927. Serial No. 292,827.

This invention is designed to improve wringer frames and bearing supports therein particularly in metal wringers formed of sheet metal. Features and details of the invention will appear from the specification and claim.

A preferred embodiment of the invention is illustrated in the accompanying drawings as follows:—

- 10 Fig. 1 shows a front elevation of the wringer.
 Fig. 2 a section on the line 2—2 in Fig. 1.
 Fig. 3 a face view of one of the side stiles.
 Fig. 4 a section on the line 4—4 in Fig. 2.
 15 Fig. 5 a section on the line 5—5 in Fig. 4.
 Fig. 6 a section on the line 6—6 in Fig. 4.
 20 1 marks the base of the frame, 2 the side stiles, 2a a plate for attaching the wringer to a support, 3 and 4 the bottom and top wringer rolls respectively, 5 the top bar, 6 the tension spring, and 7 the tension screw. These parts, except as hereinafter noted, may be of common construction. The side stiles are made up of a channel, or box form having 25 the outer face plate 8, the front and rear face plates 9 and the inner guide flanges 10 which extend along each side of a vertical slot in which the roll shafts operate, a power shaft 13 extending through a perforation 12 in 30 the outer plate 8. The lower end of the stile below the slot 11 is box-shaped. A lower bearing 14 is arranged in the side stile and rests upon lips 15 which are struck up in the sheet metal. The bearing has a metal 35 plate 16 at its lower end to form a better support for the bearing material which is usually wood. By striking up these bearing supports 15 directly in the metal on opposite walls an accurate base is provided for the 40 bearing so as to present an even bearing surface throughout the length of contact with the shaft.

The base of the wringer is of channel form open at the bottom. The upper plate, or web, 45 of the channel is separated from the side flanges at the end and the web is turned upwardly at 17 and secured to the inner wall of the side stile by spot welding. The flanges from which the web portion at 17 is separated extend along the outer faces of the

stiles at 18 and are secured to the side walls of the stiles preferably by spot welding.

The upper bearings 19 are guided in the flanged stiles and rest upon the shaft 20 of the upper roll. The spring 6 extends through 35 the slot 11 and is seated on the bearings 19.

What I claim as new is:—

In a wringer, the combination of a side stile of channel form having lips struck up on opposite walls thereof forming upwardly 60 faced shoulders; and a lower wringer bearing resting on said shoulders.

In testimony whereof I have hereunto set my hand.

VINCENT GEHRLEIN.
